UNITED STATES PATENT OFFICE.

SERN MADSEN, OF CLINTON, IOWA.

MACHINE FOR SANDING WINDOW SASHES.

Application filed November 3, 1921, Serial No. 512,677. Renewed March 29, 1928.

The object of my invention is to provide a machine for automatically sanding window sashes of comparatively simple, durable and inexpensive construction.

5 A further object is to provide in a sash sanding machine having a feed chain arranged to automatically feed the sash between suitable sanding rollers, improved means for driving and adjusting the rollers.

10 A further object is to provide in a sash sanding machine means whereby both sides of the sash and one edge of the check rail may be sanded by a single operation of the machine.

15 A further object is to provide in a sash sanding machine having a series of sanding drums, improved means for mounting the drums whereby a maximum number of sashes may be sanded by a given set of 20 drums before replacing the abrasive material thereon.

A further object is to provide in a sash sanding machine employing a series of sanding drums, improved means for driving the drums and for adjusting them relative to 25 the sash which is to be sanded.

30 A further object is to provide in a sash sanding machine having a series of sanding drums, improved means for adjustably mounting the drums relative to the sash upon which it operates, the said means being designed to carry a motor for independently driving each of said drums, the said motor to be so mounted that when the 35 said means is adjusted the motor will be correspondingly adjusted to always be in an operative relation with said drums.

These and other objects will be apparent to those skilled in the art.

40 My invention consists in the construction, arrangement and combination of the various parts of the device, whereby the objects contemplated are attained, as hereinafter more fully set forth, pointed out in my claims, 45 and illustrated in the accompanying drawings, in which:

Figure 1 is a side elevation of my improved sanding machine.

Figure 2 is a plan view of the same.

50 Figure 3 is a transverse, sectional view taken on the line 3-3 of Figure 2.

Figure 4 is an end elevation of the right hand end of Figure 1.

55 Figure 5 is an enlarged detail sectional view taken on the line 5-5 of Figure 2.

Figure 6 is an enlarged detail sectional view taken on the line 6-6 of Figure 2.

Figure 7 is a segmental and longitudinal sectional view of one of the drum supporting members.

80 Figure 8 is a detail view showing a portion of the mechanism for raising and lowering the upper group of abrasive drums.

Figure 9 is a vertical, longitudinal, sectional view of my improved sanding machine.

85 My improved machine comprises a base formed of end members 10 and side members 11. Mounted upon each of the members 11 is a frame member 12.

The left hand end of the frame members 12, as shown in Figure 1, is provided with slots 13, each of which is provided with a bearing 14 adjustably mounted in said slots by means of a set screw 15. The said bearings 14 are designed to carry a transversely arranged shaft 16. This shaft 16 is provided near each end with a sprocket 17. The opposite end of the frame 12 is provided with a transverse shaft 18 upon which 80 are mounted sprockets 19. Each corresponding set of sprockets 17 and 19 is provided with a chain 20.

85 Each of the chains 20 is designed to travel in a channel member 21 extending inwardly from the top portion of the frame members 12, as clearly shown in Figure 3.

90 Between the members 21, I have provided a platform 22, the top face of which is substantially in line with the top edges of the top runs of the chains 20. The said chains 20 are designed to carry a series of feed bars 23, the said feed bars being arranged transversely between said chains and designed to travel over the upper face of the 95 platform 22, the front edge of each of the feed bars 23 being substantially at right angles with the said chains. The lower runs of the chains 20 are designed to travel in channel members 24 secured to brackets 25 100 mounted on the side members 11 of the base.

105 The channel members 24 are placed between the members 11 so that the lower runs of the chains and feed bars will travel beneath the sanding rollers, and the mechanism for driving and supporting the same.

For driving the feed conveyor, which comprises the bars 23 and the chains 20, I have provided a belt wheel 26 on one end of the shaft 18. This belt wheel has a 110

sprocket 27 mounted on the inner end of its hub, best shown in Figures 2 and 4. The wheel 26 and the sprocket 27 are loosely mounted on said shaft.

5 Mounted on the outer face of one of the members 11, I have provided a bracket 28 on which is mounted a motor 29. The wheel 26 is driven from the motor 29 by means of a belt 30.

10 Rotatively mounted transversely adjacent to the rear end of the base 10 and beneath the shaft 18, I have provided a shaft 31, one end of which is provided with a sprocket wheel 32, while the other end is provided

15 with a smaller sprocket 33. The sprocket 32 is driven from the sprocket 27 by means of a chain 34.

Rigidly secured to the opposite end of the shaft 18 from that on which the belt wheel 26 is mounted, I have provided a sprocket wheel 35 which is driven from the sprocket 33 by means of a chain 36.

20 Thus it will be seen that the feed conveyor may be continuously driven from the motor 29 at a considerably reduced speed. The feed conveyor may be started or stopped by starting or stopping the motor 29.

25 Adjacent to the discharge end of the feed conveyor, I have provided a plate 37 having grooves 38 in line with the chains 20. This plate 37 is for the purpose of receiving a sash as it is being discharged from the feed conveyor. The channels 21 are so arranged that the chains 20 may lie in the bottom of the channels and permit the check rail of a window sash to also enter the channels, the said channel members being provided with an upwardly extending portion 39 against which a check rail 40 of a sash 41 may rest, as clearly shown in Figure 6. A bar 42 is provided for the inner flange member of the channels 21 which serves as a guide for the inner edge of the check rail 40. This bar 42 extends longitudinally with the channel members.

30 By this arrangement, it will be seen that the sash 41 may be placed on the left hand end of the platform 22, adjacent to the front edge of one of the feed bars 23 with the check rail 40 within the channels 21 and between the guides 39 and 42.

35 Thus it will be seen that the said sash may be advanced over the platform 22 and held against lateral movement by the guides 39 and 42 with the sash 41 lying flat against the platform 22.

40 For sanding the edge of the sash 41 and also the corresponding edge of the check rail 40, I have provided the following mechanism:

45 Secured to one of the members 11, I have provided a bracket 43 on which is mounted a motor 44. The armature shaft of the motor 44 is operatively connected with a transversely arranged shaft 45, Figure 5. The

opposite end of the shaft 45 is mounted in a bearing 46 mounted on the opposite plate 11 that to which the bracket 43 is attached. Each end of the shaft 45 is provided with a belt pulley 47.

50 Secured to the top edge of each of the frame members 12 above the shaft 45, I have provided a spaced set of brackets 48. The brackets 48 and the mechanism carried thereby are alike and but one of them will be described. The said brackets are so located that the shaft 45 and the motor 44 will lie in a vertical plane substantially equidistant between said brackets.

55 Each of the brackets 48 is provided with two sets of pivoted arms 49. The upper ends of each set of arms are designed to carry a pivotally mounted bearing 50. Rotatively mounted in each set of the bearings 50 is a shaft 51 having a belt wheel 52.

60 The belt wheels 52 are driven from the wheel 47 by means of a belt 53, the lower run of which extends under the pulley 47, and the upper run of which is designed to pass beneath an idler pulley 59 which is adjustable in the usual manner for the purpose of keeping a belt tight.

65 A thrust collar 54 is mounted on the shaft 51 adjacent to the inner face of the inner bearing 50.

70 Mounted on the inner end of the shaft 50, I have provided a disc 55, the inner face of which is provided with an abrasive material 56, the face of said abrasive material being designed to rest adjacent to the outer edge of the sash 41 so that as the sash is moved past the disc 55, the outer edge of said sash will become finished.

75 For adjusting the disc 55, I have provided an arm 57 mounted to the outer end of each of the outer bearings 50. This arm 57 extends downwardly and has a set screw 58 which is screwed into the outer end of the bracket 48.

80 By adjusting the screw 58, the bearings 50 may be moved inwardly or outwardly, and thereby provide means for adjusting the depth of the cut of the abrasive 56.

85 In this connection it will be noted that the platform 22 is of a width greater than the width of the sash, thus permitting but one edge of the sash to engage the discs 55.

90 By providing a set of abrasive discs at each side of the platform 22, I have provided means whereby half of the sash may be made to engage one set of discs while the other half may be made to engage the opposite set. The purpose of this will be hereinafter made clear.

95 At the central portion of each of the frame members 12, I have provided a series of vertical guide members 60. These guide members are arranged in pairs, and each pair is designed to slidably receive a bearing member 61. Each set of corresponding bearings

61 is designed to receive a slideable and rotative shaft 62, best shown in Figure 3.

The central portion of the shaft 62 is provided with an abrasive drum 63 which is so mounted that the upper face of said drum will extend through suitable slots in the platform 22 and engage the under face of the sash 41. This drum is of a length slightly less than the distance between the inner edges of the guide members 21 so that a slight longitudinal movement of the drum 63 will be permitted.

Mounted on the corresponding members 61 and beneath the drum 63, I have provided a tube 64. This tube is shown in section in Figure 7, and is rigidly mounted in the bearing members 61.

The bottom portion of the tube 64 is provided with openings 65 which are immediately above openings 66 in the bottom portion of the member 61. Each corresponding set of openings 65 and 66 is designed to receive a pin 67, the lower end of which rests on the bottom of the groove in which the member 61 is mounted. The upper ends of the pins 67 are each provided with a beveled top portion.

Slidably mounted within the tube 64 near the right hand end, as shown in Figure 7, I have provided a block 68 having its lower face beveled and designed to rest upon the right hand pin 67.

Slidably mounted within the tube 64 above the left hand pin 67, I have provided a block 69 similar to the block 68.

This block 69 is provided with a tubular sleeve 70, the outer end of which is screw threaded and designed to receive a sleeve 71. The sleeve 71 is provided with a hand wheel 72 for rotating the same.

The outer face of the sleeve 71 is screw threaded in the opposite direction from the inner face and designed to coat with a screw threaded portion 73 in the left hand end of the tube 64.

The left hand end of the tube 70 is provided with an internal screw threaded portion 74 in which is mounted a sleeve 75. The outer end of the sleeve 75 is provided with a head 76 which is for the purpose of rotating the said sleeve within the tube 70.

The sleeve 75 is provided with a screw threaded opening 77 threaded in the opposite direction from the outer face of said sleeve, and designed to receive the left hand screw threaded end of a rod 78. The outer end of the rod 78 is provided with a lock nut 79. The opposite end of said rod 78 is provided with a screw threaded portion 81 mounted in the block 68, the outer end of the portion 81 being provided with a nut 82 for the purpose of locking the block in position.

By this arrangement, it will be seen that if the hand wheel 72 is rotated, it will move longitudinally either to the left or right de-

pending on which direction it is rotated relative to the tube 64. The sleeve 70 will be moved to the right or left and with it the rod 78 through the sleeve 75, thereby providing means whereby the blocks 68 and 69 will be moved simultaneously and longitudinally within the tube, and the said tube elevated or lowered upon the pins 67, thereby providing means for raising or lowering the drum 63 through the members 61.

When it is desired to raise or lower the right hand end of the drum 63, as shown in Figure 3, without raising or lowering the opposite end for the purpose of alining the top face of the drum, this I can accomplish by loosening the nut 79 and rotating the head 76, which in turn will rotate the sleeve 75 within the tube 70 and about the left hand end of the rod 78, the outer portion and the inner portion of the sleeve 75 being threaded in the opposite direction will cause the rod 78 to be moved longitudinally through the block 69 and the tube 70, and the block 68 to be moved longitudinally and the right hand end of the said tube either raised or lowered. After it has been raised or lowered a desired amount, the nut 79 may then be tightened and the adjustment positively secured.

If it is desired to adjust the left hand end of the drum 63, the wheel 72 is rotated as before described, which will cause both of the blocks 68 and 69 to be moved and the drum 63 elevated or lowered, after which the adjustment of the right hand end may then be made as before described.

This provides means for accurately alining the top face of the drum with the top face of the platform 22, so that the drum 63 may be made to cut any desired depth.

For rotating the drum 63, I have provided a motor 83 mounted on a bracket 84 which is mounted on an eccentric sleeve 85 near the left hand end of the tube 64. The bracket 84 is provided with an inwardly extending arm 86, which is loosely bolted to the member 61 so that a slight up and down movement of the member 84 may be permitted, and yet the said member may be held against rotation upon the sleeve 85.

The bracket 86 is secured to the member 61 by means of a set screw 87 so arranged that lateral movement of the member 86 may also be provided.

The left hand end of the shaft 62 is provided with an armature or rotor 88 which is rigidly secured to the shaft. The said armature is capable of moving longitudinally in a field or stator 89 so as to permit longitudinal movement of the drum 63. The screw 87 and the sleeve 85 provide means whereby the field may be alined with the armature. This provides means whereby the drum 63 may be positively driven without the use of belts or gears, and where-

by the said drum may be easily and quickly elevated or lowered without interfering with the alinement of the motor.

For producing longitudinal movement of the shaft 62, I have provided a shaft 90 rotatively mounted adjacent to the right hand base member 11, as shown in Figures 3 and 4. This shaft is secured in position by means of brackets 91, and has its front end 10 provided with a beveled gear 92 which is designed to mesh with a beveled gear 93 on the shaft 31.

Mounted on the shaft 90 beneath the shaft 62, I have provided an eccentric 94 15 which is designed to carry an eccentric block 95. This block 95 is provided with an opening 96 in which is slidably mounted a rod 97, the central portion of which is pivoted to the outer end of a link 98, the inner end 20 of said link being pivoted to the bearing member 61 by means of a pin 99.

The right hand end of the shaft 62 is provided with a sleeve 100 which is secured on the shaft by means of a nut 101 and a washer 25 102. The said sleeve 100 is designed to carry a ring 103.

Secured to the upper end of the member 97, I have provided a bifurcated arm 104, the upper end of which is pivotally connected to the ring 103.

The member 104 is secured to the upper end of the arm 97 by means of a pivot 105 and a bolt 106 mounted in a slot 107.

By this arrangement, it will be seen that 35 when it is desired to adjust the reciprocating path of the drum 63 laterally with the movement of the sash through the machine, the operator may loosen the nut 106 and swing the upper end of the arm 104 either to the right or left, then locking the said nut. The drum 63 may then be reciprocated near one side or the other of the conveyor member. The object of this is to overcome the difficulty which is experienced by the ends of the 40 dowel pins of the sash engaging the sand paper and wearing grooves therein. The reciprocating movement of the drum has a tendency to widen the path formed by the ends of the dowel pins engaging the abrasive material of the drum, and thereby lengthen the 45 life of the abrasive material. The sash bars which extend longitudinally with the movement of the sash through the machine also have a tendency to wear grooves in the abrasive material due to the fact that they engage the abrasive material a greater length 50 of time than the transversely arranged bars.

After the abrasive material has been worn through, the drum may be then adjusted a 55 slight distance longitudinally and the dowel pins made to inscribe a different path about the surface of the abrasive drums. The member 97 is caused to oscillate by the rotation of the shaft 90 and the eccentric 94 within the block 95. The drums 63 are arranged

at a slight angle relative to the transverse line through the machine, as clearly shown in Figure 2.

This provides means whereby the sash is carried more uniformly through the machine 70 and vibration eliminated that would otherwise be caused by the cross members of the sash successively and abruptly engaging the abrasive rollers.

For yieldingly holding the sash against 75 upward movement when engaged by the upper face of the drum 113, I have provided a series of spring arms 108 which are secured to a transversely arranged bar 108^a. For this purpose, yieldably mounted rollers may 80 also be used if so desired. I have preferably provided three of these drums 63 designed to engage the under surface of the sash.

For sanding the upper surface of the sash, I have provided the following mechanism: 85

Adjacent to the right hand end of each of the members 12, Figure 1, I have provided a frame member 110. Adjacent to the right hand end of each of the members 110 is a stationary frame member 111. Each of the 90 frame members 110 is mounted to move vertically between the members 12 and 111.

Each of the members 110 is provided with a series of vertically adjustable members 112 similar to the members 61, and designed to 95 carry abrasive drums 113 similar to the drums 63 and mounted in the same manner and by similar mechanism with the exception that the drums 113 are designed to engage the upper face of the sash instead of the lower face, each of the drums 113 being provided with an independently driven motor 114 similar to the motors 83.

Each of the members 110 is mounted on a pair of jack screws 115 which have their 105 base members rigidly mounted on the upper edge of the members 11. Each of the screws 115 is screw threaded into said base member and is provided with a sprocket wheel 116 which is keyed thereon and has the upper 110 end of its hub designed to engage the lower edge of the frame 110 in such a manner that as the sprockets 116 are rotated, the frame members 110 will be raised or lowered.

All of the sprockets 116 are designed to receive a chain 117 so that as one of the sprockets 116 is operated, all will be operated simultaneously, thereby providing means whereby the drums 113 may be simultaneously 115 raised or lowered.

On the base member 11 I have provided beveled gears 118 on the shaft 90, Figures 2 and 8, which are slidably mounted and designed to mesh with a beveled gear 119 mounted on one end of a transverse shaft 120, the beveled gears 118 being mounted on a sleeve 121 which is feathered to the shaft 90 and operated by means of a lever 122 so that as the sleeve 121 is moved in either direction, the gear 119 will be en- 125 120

gaged and the shaft 120 caused to rotate in either direction.

The opposite end of the shaft 120 is provided with a worm 123 operatively connected with a gear 124 keyed to the right hand screw 115, as shown in Figure 1, thereby providing means whereby the adjacent sprocket wheel 116 may be rotated, and which in turn will cause the chain 117 to be operated and the frame 110 elevated or lowered as above described.

Thus it will be seen that the drums 113 may be easily and quickly adjusted to sash of different thickness, and each drum may be individually adjusted to the sash by the mechanism before described for the drums 63.

In the practical operation of my machine, assuming that all of the motors are in operation, then the slats 23 would be moved longitudinally through the machine above the platform 22. The operator then places a sash on the platform 22 in front of one of the slats 23 with the check rail within the chain groove of one of the members 21, as clearly shown in Figure 6. The next sash is laid with the check rail in the groove of the opposite member 21 so that the check rail of one sash is adjacent to one side of the machine, while the check rail of the opposite sash is adjacent to the opposite side of the machine.

The sash is then advanced until the check rail engages the discs 55, and the edge of the sash is sanded.

The sash is then advanced under the fingers 108 and above the drums 63, thence carried beneath the drums 113, and then delivered to the platform 37.

Each of the drums 113 is independently operated and is moved longitudinally with its shaft. The drums 113, however, are longer than the drums 63 so as to engage the upper face of the longitudinal rails of the sash while the drums 63 engage all the longitudinal rails of the sash except the check rail, as clearly shown in Figure 3, the

drums 113 being shown in dotted lines in said figure.

By this arrangement, it will be seen that 50 a sash may be placed in the machine at one end, and come out completely sanded at the opposite end, and it provides means whereby the maximum amount of wear may be obtained from the abrasive material of the 55 drum, due to the fact that the drums are adapted to be shifted in different positions whenever desired, or whenever the abrasive material has been worn through by dowel pins or by the longitudinal bars of the sash. 60

I claim as my invention:

1. In a sanding machine, a frame, a stock-carrying platform, a second frame adjustably mounted in the first said frame, said second frame being designed to carry a 65 shaft arranged substantially transversely with said platform, means for adjusting the said second frame to move the abrasive drum toward said platform, a motor frame supported on said second frame, a motor armature on one end of said shaft designed to be operatively mounted within said motor frame, and means for imparting axial reciprocation to said shaft and to said armature. 70

2. In a sanding machine, a frame, a stock-carrying platform, a second frame adjustably mounted in the first said frame, said second frame being designed to carry a shaft arranged substantially transversely with 80 said platform, means for adjusting the said second frame to move the abrasive drum toward said platform, a motor frame supported on said second frame, a motor armature on one end of said shaft designed to be 85 operatively mounted within said motor frame, means for adjusting said motor frame relative to said second frame and to said armature for the purpose of centering the armature and the said motor frame, and means for imparting axial reciprocation to said shaft and to said armature. 90

SERN MADSEN.
